RALPH Z. HOPKINS AND EARL F. SEGER, OF DETROIT, MICHIGAN, ASSIGNORS TO HUDDSON MOTOR CAR COMPANY, OF DETROIT, MICHIGAN, A CORPORATION OF MICHIGAN.

STENCIL

Application filed February 25, 1928. Serial No. 256,975.

This invention relates to stencils, and more particularly stencils for use in striping automobile window reveals.

An object of the invention is to provide a device of the foregoing character comprising a frame structure having means for accurately positioning or centering it within a window reveal, together with means for clamping the frame in position, said frame being of a character permitting it to conform to the exterior contour of the reveal when clamped in position. Another object of the invention is to provide a sectional frame in which the sections are contiguous and spaced to provide a continuous slot permitting the application of an uninterrupted stripe to the window reveal.

The invention will be more fully understood from the following description when taken in connection with the accompanying drawings and the novel features thereof will be pointed out and clearly defined in the claims at the close of this specification.

In said drawings:

Fig. 1 is a front elevation of the stencil.
Fig. 2 is a section on the line 2—2 of Fig. 1.

Fig. 3 is a view similar to Fig. 2 with the stencil clamped in its position of use.

Fig. 4 is an enlarged fragmentary detail, partly in section of one corner of the stencil.

Fig. 5 is a section taken along the line 5—5 of Fig. 1.

Fig. 6 is a vertical section through the stencil clamped in position upon the window reveal and illustrating the method of applying the stripe to the reveal.

Fig. 7 is a front elevation of an unstriped body panel and window reveal.

Fig. 8 is a view similar to Fig. 7 after the stripe has been applied.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practiced or carried out in various ways.

Also it is to be understood that the phrase-

ology or terminology employed herein is for the purpose of description and not of limitation, and it is not intended to limit the invention beyond the terms of the several claims hereto appended or the requirements of the prior art.

Heretofore, it has been common practice to apply a stripe to automobile window reveals by hand with a pencil-like brush. The operation has been a slow and tedious one and since the stripes have usually been applied free hand, it has been impossible to apply them with any certainty of uniformity. In accordance with our invention, the stencil is clamped in place within the window reveal and an air or other pressure operated paint nozzle or brush employed to apply the stripe, the stencil providing a continuous slot or space around the reveal where the stripe is to be applied. The operation of striping reveals therefore is an extremely simple one when effected in accordance with our invention and moreover, the stripes are uniform. Another advantage of striping in accordance with this invention is that inexperienced workmen or relatively inexpensive labor can be employed to stripe the reveals.

Referring now to the drawings, A represents as a whole the stencil of our invention, B the body panel and C the window reveal, so the completed stripe being shown at S in Fig. 8.

The stencil comprises preferably a flexible portion including two metal contiguous sections 10 and 11 spaced to provide an uninterrupted slot or opening 12 therebetween. The sections 10 and 11 are preferably interconnected by means of a plurality of spring-like members 13 which may, if desired, be U-shaped. The ends of these spring members may be welded to the respective sections or connected therewith in any other suitable manner. The inner face of the section 10 is provided with a preferably continuous strip of fabric 14 secured thereto in any suitable manner. A plurality of preferably wooden blocks or the like 15 are secured to the outer face of the fabric strip 14 (Fig. 4), such as by glue or other adhesive material or in any other suitable manner, these blocks extending

entirely around the inner face of the section. Thus it will be seen that the sections 10 and 11 are capable of being flexed relative to one another, enabling the device to fit curved or other than plane surfaces.

In addition to the foregoing, we provide means for supporting the stencil and clamping it in position within the window reveal. Such means comprises preferably a rectangular frame shown as a whole at F consisting of longitudinal members or bars 16 and transverse bars 17 which are interconnected at their ends by means of strips or members 18. The transverse bars or end members 17 are connected to one another through the medium of additional longitudinal members 19 which may be in the form of channel bars. The longitudinal members 16 and 19 are further interconnected by means of bars or strips 20 each of which is provided with a slot or aperture 21 (Figs. 5 and 6).

The frame F and the section 10 are resiliently connected together in spaced relation by means of a plurality of coil springs 22 having their opposite ends embedded in the frame and section respectively.

Each of the bars 20 is provided with a clamping device comprising preferably a metal rod or bolt 23 carrying at its outer end a pivoted cam-like clamping member 24 including a handle for operating it, and at its inner end with a swinging bar or member 25 which is maintained in position upon the shaft or bolt by nuts 26.

To apply the stencil to a window reveal, the bars 25 are moved in the direction of the arrows to the position in which they are shown in Fig. 1 and the device inserted in place. As shown in Fig. 6, upon insertion of the device, the blocks or members 15 engage the inner surrounding wall of the window reveal and serve to center the stencil. Moreover, it will be seen (Fig. 6) that when the clamping members 24 are moved to the position in which they are shown in that figure, the frame F and the sections 10 and 11 of the stencil are moved toward one another against the action of the springs 22, with the bars 25 engaging the inner face of the body panel about the window reveal. Moreover, it will be noted that when the device is clamped in position the sections 10 and 11 are caused to flex and conform to the contour of the outer face of the body panel about the window reveal, the outer section 11 being maintained in fixed spaced relation with respect to the inner section 10 by means of the spring interconnecting members 13. When the device is in the position of Fig. 6, it will be seen that the uninterrupted slot or opening 12 extends completely and continuously around the window reveal, this uninterrupted space being provided through the medium of the preferably U-shaped spring members 13

which maintain the sections 10 and 11 in spaced relation. With the stencil now clamped in position, the operator employs an air or other pressure operated paint nozzle or brush shown as a whole at D to apply the stripe to the window reveal by simply following the outline of the slot 12 entirely around the stencil, thus producing a stripe such as that shown at S in Fig. 8. After the stripe has been applied the clamping members 24 are released, the bars 25 returned to the position in which they are shown in broken lines in Fig. 1 and the stencil removed from engagement with the window reveal.

Thus, it will be seen that we have provided an inexpensive stencil capable of being quickly and accurately applied to a window reveal permitting the striping operation to be effected in a minimum of time, and which may be quickly removed and applied to another window reveal to effect a similar striping operation.

We claim:

1. A stencil for use in striping automobile window reveals, comprising a frame, a flexible extension carried by said frame adapted to overlap the face of said reveal, said extension having a continuous striping space, means for centering the stencil within the window reveal, and means for clamping the stencil in position.

2. A stencil for use in striping automobile window reveals, comprising a frame, a flexible extension carried by said frame adapted to overlap the face of said reveal, said extension comprising a pair of contiguous connected members spaced to provide an uninterrupted slot adapted to overlie the face of said reveal, means for centering the stencil within the window reveal, and means for clamping the stencil in position.

3. A stencil for use in striping automobile window reveals, comprising a frame, a flexible extension carried by said frame adapted to overlap the face of said reveal, said extension comprising a pair of contiguous spring connected members spaced to provide an uninterrupted slot adapted to overlie the face of said reveal, means carried by said extension for centering the stencil within the window reveal, and means for clamping the stencil in position.

4. A stencil for use in striping automobile window reveals, comprising a frame, a flexible extension carried by said frame adapted to overlap the face of said reveal, flexible means carried by said extension for centering the stencil within the window reveal, said extension having a continuous striping space, and means for clamping the stencil in position.

5. A stencil for use in striping automobile window reveals, comprising a frame, a flexible extension carried by said frame adapted to overlap the face of said reveal and having

spaced blocks for centering the stencil within the reveal, said extension having a continuous striping space, and means for clamping the stencil in position.

5 6. A stencil for use in striping automobile window reveals, comprising a frame, a flexible extension carried by said frame adapted to overlap the face of said reveal, means carried by said extension for centering the 10 stencil within the reveal, said extension having a continuous striping space, and means for clamping the stencil in position, whereby said frame and flexible extension are caused to conform to the contour of said reveal.

15 7. A stencil for use in striping automobile window reveals, comprising a frame, a flexible extension carried by said frame adapted to overlap the face of said reveal, said extension comprising a pair of contiguous members spaced to provide an uninterrupted slot adapted to overlie the outer face of said reveal, substantially U-shaped springs for interconnecting said members, means carried 20 by one of said members for centering the stencil within the reveal, and means for clamping the stencil in position.

In testimony whereof we affix our signatures.

30 RALPH Z. HOPKINS.
EARL FENTON SEGER.
